UNITED STATES PATENT OFFICE.

DENIS F. O'BRIEN, OF NEWARK, NEW JERSEY.

HYDRANT.

SPECIFICATION forming part of Letters Patent No. 694,298, dated February 25, 1902.

Original application filed April 27, 1900, Serial No. 14,577. Divided and this application filed December 14, 1900. Serial No. 39,859. (No model.)

To all whom it may concern:

Be it known that I, DENIS F. O'BRIEN, a citizen of the United States, residing at Newark, county of Essex, and State of New Jersey, 5 have invented certain new and useful Improvements in Hydrants, fully described and represented in the following specification and the accompanying drawings, forming a part of the same.

10 The invention of this application (which is a division of an application filed by me April 27, 1900, Serial No. 14,577) relates to improvements in hydrants, and particularly hydrants of that class known as "compression - hydrants"—that is, hydrants in which the main valve is held to its seat by the pressure of water behind it.

15 The object of the present invention is to provide a hydrant of this class in which the main valve and connected parts are so constructed and arranged in the hydrant-casing that the main valve may be readily removed from or inserted in the casing without taking the latter apart, and, further, to provide an 20 inserting and removing tool for the main valve which will not only unscrew it from or screw it into the opening provided in the casing for receiving it, but will also interlock with the main valve in such way as to support 25 it while being removed from or inserted in the casing.

30 In the accompanying drawings, Figure 1 is a sectional elevation of a hydrant provided with a main valve constructed in accordance 35 with the present invention. Fig. 2 is a similar view with the upper part of the hydrant or hydrant-casing removed and illustrating a main-valve removing and inserting tool constructed in accordance with the present invention inserted in the casing. Fig. 3 is an elevation of the lower portion or foot of the main-valve removing and inserting tool, illustrating particularly the means with which it is provided for engaging and rotating the 40 valve and connected parts to screw them into or out of position in the casing. Fig. 4 is a bottom plan view of the same. Fig. 5 is a plan view of a seat-ring for the main valve.

45 Referring to said drawings, the hydrant or 50 hydrant-casing therein shown comprises a casing or stand-pipe 1, provided with the

usual hose-nozzles 2 3, a main-valve casing 4, and a removable cap 5.

6 represents the main valve, the seat 7 of which is formed in an exteriorly-threaded 55 ring 8, screwed into the main-valve casing, said main valve 6 being also provided with vertical guides 9 for maintaining it in proper relation to its seat when the valve is being closed or opened. The mechanism for opening and closing the main valve includes a spindle 10, secured to the valve 6, and an actuating-spindle 11, connected at its lower end with the spindle 10, so that as the spindle 11 is rotated the spindle 10 rotates with it. The 60 spindle member 11, which, as will be observed, passes through an opening in a bridge 13 and a stuffing box or gland 14 above the same, is threaded at its upper end for connection with a turning-nut 12 and also for connection 65 with a removing-tool, hereinafter described, whereby the spindle, main valve, and the latter's seat-ring are locked to and supported by the removing-tool when the latter is inserted in the hydrant-casing for the purpose 70 of inserting or removing the main valve, as will hereinafter more fully appear.

75 The hydrant and main-valve-operating mechanism shown and thus far briefly described are not claimed herein, as they form 80 the subject-matter of my aforesaid application, wherein they are more fully described.

85 For the purpose of providing for the ready removal and insertion of the main valve without taking apart the hydrant-casing or removing the stand-pipe 1 I construct the ring 8, containing the valve-seat 7, with vertical lugs 31, and also provide a tool adapted to engage said lugs 31 and through them to rotate the ring 8 and screw it into or unscrew it from 90 the main-valve casing. This tool consists of a pipe 32, adapted to be passed over the spindles 10 11 and provided at its upper end with a head 33, bearing handles 34, by which the pipe 32 may be rotated, and at its lower 95 end with feet or lugs 35, adapted to engage with the lugs 31 on the ring 8 to rotate the latter and unscrew it from or screw it into position in the casing. To insert the tool into the hydrant-casing in engagement with the 100 ring 8, the only parts of the hydrant which it is necessary to remove are the cap 5, turn-

ing-nut 12, bridge 13, and arm 28. The pipe 32 is then passed over the spindles 10 11 and held in position by the return to the spindle 11 of the turning-nut 12, as shown in Fig. 2, 5 which by reason of its engagement with the threaded end of spindle 11 locks the main valve and its seat-ring 8 to the removing-tool 32, so that they will be supported by the latter while being passed inwardly or outwardly 10 through the stand-pipe 1 to introduce them into or remove them from the hydrant. The tool 32 being turned will by the engagement of its feet 35 with projections 31 on valve-seat ring 8 rotate the latter, and thus screw 15 it into or unscrew it out of engagement with the main-valve casing. When unscrewed, the seat-ring 8 and main valve 6 are supported and lifted out of the stand-pipe 1 by means of the removing-tool 32 and reintroduced by 20 the same means. The pipe 32 is maintained in vertical position or centered by means of a guide 36, secured to the spindle 10, aided by the bracket 18.

What I claim is—

- 25 1. In a hydrant, the combination with its stand-pipe, of a main-valve mechanism capable of being passed inwardly and outwardly through the stand-pipe to introduce it into and remove it from the hydrant and provided 30 with a screw-threaded member for connection to the hydrant and with means for interlocking with a removing and inserting tool whereby said screw-threaded member may be rotated to connect it to or disconnect it from the hydrant and with means whereby said valve mechanism may also be supported by the tool while being introduced into or removed from the hydrant, substantially as described.
- 35 2. In a hydrant, the combination with its stand-pipe, of a main-valve mechanism capable of being passed inwardly and outwardly through the stand-pipe to introduce it into and remove it from the hydrant and provided with 40 a screw-threaded seat-ring for connection to the hydrant and with an operating-spindle, said threaded member and spindle being provided with means for interlocking with a removing and inserting tool whereby said screw-threaded member may be rotated to connect it to or disconnect it from the hydrant and with means whereby said valve mechanism may also be supported by the tool while being introduced into or removed from the hydrant, substantially as described.
- 45 3. In a hydrant, the combination with its stand-pipe, of a main-valve mechanism capable of being passed inwardly and outwardly through the stand-pipe to introduce it into and remove it from the hydrant and provided with a screw-threaded seat for connection to the hydrant and with an operating-spindle, said threaded member being provided with means for interlocking with a removing and inserting tool whereby said threaded member may be rotated to connect it to or disconnect it from the hydrant and said spindle being provided with means for interlocking with said tool whereby said valve mechanism may be supported by the tool while being introduced into or removed from the hydrant, and an inserting and removing tool adapted to so interlock with said valve-seat ring and spindle, substantially as described.
- 50 4. In a hydrant, the combination with its stand-pipe, of a main-valve mechanism capable of being passed inwardly and outwardly through the stand-pipe to introduce it into and remove it from the hydrant and provided with a screw-threaded seat-ring for connection to the hydrant and with an operating-spindle, said threaded member and spindle being provided with means for interlocking with a removing and inserting tool whereby said threaded member may be rotated to connect it to or disconnect it from the hydrant and said spindle being provided with means for interlocking with said tool whereby said valve mechanism may be supported by the tool while being introduced into or removed from the hydrant, and an inserting and removing tool adapted to so interlock with said valve-seat ring and spindle, substantially as described.
- 55 5. In a hydrant, the combination with its stand-pipe, of a main-valve mechanism capable of being passed inwardly and outwardly through the stand-pipe to introduce it into and remove it from the hydrant and provided with a screw-threaded seat for connection to the hydrant and with an operating-spindle, said threaded member being provided with means for interlocking with a removing and inserting tool whereby said threaded member may be rotated to connect it to or disconnect it from the hydrant and said spindle being provided with means for interlocking with said tool whereby said valve mechanism may be supported by the tool while being introduced into or removed from the hydrant, and an inserting and removing tool adapted to so interlock with said valve-seat ring and spindle, substantially as described.
- 60 6. In a hydrant, the combination with its stand-pipe, of a main-valve mechanism capable of being passed inwardly and outwardly through the stand-pipe to introduce it into and remove it from the hydrant and provided with a screw-threaded seat for connection to the hydrant and with an operating-spindle, said threaded member being provided with means for interlocking with a removing and inserting tool whereby said threaded member may be rotated to connect it to or disconnect it from the hydrant and said spindle being provided with means for interlocking with said tool whereby said valve mechanism may be supported by the tool while being introduced into or removed from the hydrant, and an inserting and removing tool adapted to so interlock with said valve-seat ring and spindle, substantially as described.
- 65 7. A tool for removing or inserting main valves and externally-screw-threaded valve-seats in hydrants, comprising a body portion adapted to be inserted into the stand-pipe of a hydrant and means for locking it to the main-valve spindle to support the latter and its valve-seat while being introduced into or withdrawn from the hydrant, said body portion being also provided with means for en-

vided with means for interlocking with said tool whereby said valve mechanism may be supported by the tool while being introduced 70 into or removed from the hydrant, substantially as described.

4. In a hydrant, the combination with its stand-pipe, of a main-valve mechanism capable of being passed inwardly and outwardly 75 through the stand-pipe to introduce it into and remove it from the hydrant and provided with a screw-threaded member for connection to the hydrant and with means for interlocking with a removing and inserting tool whereby 80 said screw-threaded member may be rotated to connect it to or disconnect it from the hydrant and whereby said valve mechanism may also be supported by the tool while being introduced into or removed from the hydrant 85 and an inserting and removing tool adapted to so interlock with said valve mechanism, substantially as described.

5. In a hydrant, the combination with its stand-pipe, of a main-valve mechanism capable of being passed inwardly and outwardly 90 through the stand-pipe to introduce it into and remove it from the hydrant and provided with a screw-threaded seat-ring for connection to the hydrant and with an operating- 95 spindle, said threaded member and spindle being provided with means for interlocking with a removing and inserting tool whereby said screw-threaded member may be rotated to connect it to or disconnect it from the hydrant and whereby said valve mechanism may also be supported by the tool while being introduced into or removed from the hydrant, and an inserting and removing tool adapted to so interlock with said valve-seat 100 ring and spindle, substantially as described.

6. In a hydrant, the combination with its stand-pipe, of a main-valve mechanism capable of being passed inwardly and outwardly 105 through the stand-pipe to introduce it into and remove it from the hydrant and provided with a screw-threaded seat for connection to the hydrant and with an operating-spindle, said threaded member being provided with means for interlocking with a removing and 115 inserting tool whereby said threaded member may be rotated to connect it to or disconnect it from the hydrant and said spindle being provided with means for interlocking with said tool whereby said valve mechanism may be supported by the tool while being introduced into or removed from the hydrant, and an inserting and removing tool adapted to so interlock with said valve-seat ring and spindle, substantially as described.

7. A tool for removing or inserting main valves and externally-screw-threaded valve-seats in hydrants, comprising a body portion adapted to be inserted into the stand-pipe of a hydrant and means for locking it to the main-valve spindle to support the latter and its valve-seat while being introduced into or withdrawn from the hydrant, said body portion being also provided with means for en-

gaging the valve-seat ring and screwing it into or out of position, substantially as described.

8. In a hydrant, the combination with its stand-pipe, of a main valve and spindle, a screw-threaded valve-seat ring provided with lugs, and a tool for removing or inserting the valve and seat-ring comprising a body portion adapted to be inserted into the hydrant and to be secured to the main-valve spindle to support the latter and its valve-seat while being introduced into or withdrawn from the hydrant, said body portion being provided with lugs for engaging the lugs on the valve-seat ring and screwing it into or out of position, substantially as described.

9. The combination with a stand-pipe, as 1, of valve 6, valve-seat ring 8 provided with lugs 31, a valve-spindle threaded at its upper

end to receive a nut, and a tool for removing or inserting the valve and its seat consisting of tube 32, provided with lugs 35 for engaging lugs 31, substantially as described.

10. The combination with a stand-pipe, as 1, of valve 6, valve-seat ring 8 provided with lugs 31, a valve-spindle threaded at its upper end to receive a nut, and a tool for removing or inserting the valve and its seat consisting of tube 32, provided with lugs for engaging lugs 31, and guide 36 on the spindle, substantially as described.

In testimony whereof I have hereunto set my hand in the presence of two subscribing witnesses.

DENIS F. O'BRIEN.
